UNITED STATES PATENT OFFICE.

THOMAS M. DUDGEON, OF CRAFTON, PENNSYLVANIA, ASSIGNOR TO PITTSBURGH STOVE AND RANGE COMPANY, OF PITTSBURG, PENNSYLVANIA, A CORPORATION OF PENNSYLVANIA.

DESIGN FOR A FIREPLACE-FRONT.

SPECIFICATION forming part of Design No. 36,065, dated September 9, 1902.

Application filed July 29, 1902. Serial No. 117,584. Term of patent 7 years.

To all whom it may concern:

Be it known that I, THOMAS M. DUDGEON, a citizen of the United States, residing at Crafton, in the county of Allegheny and State of Pennsylvania, have invented a new, original, and ornamental Design for Fireplace-Fronts, of which the following is a full, clear, and exact description, reference being had to the accompanying drawing, forming part hereof, in which the invention is illustrated in front elevation.

The leading features of my design consist of a frame the sides and cross-piece of which have a molded outer edge or border and a plain inner edge. The sides are ornamented with censers depending from garlands of flowers caught up at the corners by scrolls extending from the central portion of the hood-like cross-piece, the garlands extending across the hood. The hood has at its center a casket bearing a head with features that resemble those of both the human and the animal. The center or summer front has a raised bead near its outer edges formed of straight portions ending at the corners in volutes, between which and extending inwardly at each of the four corners is a trefoil. Dis-

posed centrally within this border is an oval panel displaying a shepherd picture consisting of the figures of a man, woman, dog, and lamb. At the sides of the panel are ornaments pierced by torches bearing streamers. Below the summer front is the grate-front, the sides of which are formed of scrolls resembling somewhat an urn in appearance. Between these sides the frame is open-work, the panels intermediate the openings being ornamented. Over the openings are small hooded portions. Below the grate-front and extending forwardly is another open-work frame having rounded corners and end ornaments and a lower convex ornamented border-piece.

I claim—

The ornamental design for a fireplace-front as herein described and shown.

In testimony whereof I have hereunto set my hand in the presence of two subscribing witnesses.

THOMAS M. DUDGEON.
